UNITED STATES PATENT OFFICE.

NILS H. ANDERSON, OF HARTFORD, CONNECTICUT, ASSIGNOR, BY MESNE ASSIGNMENTS, TO THE NOISELESS TYPEWRITER COMPANY, OF MIDDLETOWN, CONNECTICUT, A CORPORATION OF CONNECTICUT.

PAPER-FEEDING MECHANISM FOR TYPE-WRITERS.

1,175,915.

Specification of Letters Patent. Patented Mar. 21, 1916.

Application filed May 22, 1908. Serial No. 434,223.

To all whom it may concern:

Be it known that I, NILS H. ANDERSON, a citizen of the United States, residing at Hartford, in the county of Hartford and State of Connecticut, have invented certain new and useful Improvements in Paper-Feeding Mechanism for Type-Writers, of which the following is a full, clear, and exact description, such as will enable others skilled in the art to which it appertains to make and use the same.

This invention relates to the paper feeding mechanism of typewriters, and more particularly to the pressure rollers, and the means for releasing the same.

One of the objects of the invention is to provide improved means for guiding the paper about the platen roll and for holding it in contact therewith.

Another object is to provide means which may be conveniently manipulated to release the paper when desired.

Other objects will be in part obvious and in part pointed out hereinafter.

The invention accordingly consists in the features of construction, combinations of elements and arrangement of parts which will be exemplified in the construction hereinafter set forth, and the scope of the application of which will be indicated in the following claims.

In the accompanying drawings wherein is illustrated one of various possible embodiments of my invention, Figure 1 represents a plan view of the platen carriage of a typewriting machine, showing the improved paper feed construction. Fig. 2 is a front elevation thereof. Fig. 3 is a view in section taken on line 3—3 of Fig. 4. Fig. 4 is a transverse sectional view taken on line 4—4 of Fig. 1. Fig. 5 is a view similar to Fig. 4, but showing the feed rollers disengaged from the platen roll. Fig. 6 is a view in section taken on line 6—6 of Fig. 1, showing the feed rollers disengaged from the platen. Fig. 7 is a sectional view taken on line 7—7 of Fig. 1, showing a detail of construction. Fig. 8 is a similar view taken on line 8—8 of Fig. 1, showing the spring device for holding the feed rollers in engagement with the platen roll.

Similar reference characters refer to simi-

lar parts throughout the several figures of the drawings.

Referring now to the drawings, wherein, for convenience the platen frame is broken away and but one set of feeding devices shown, 1 indicates the platen frame, a portion of which is formed by longitudinally extending rails 2 and 3, which connect the side pieces 4 and 5 of said frame. The platen roll is shown at 6, and has its shaft 7 journaled as usual in the side walls of the platen frame, the platen, in the present instance, being constituted by a thin strip of metal 8 extending between the side members of the platen frame, and lying in contact with the platen roll. A paper table is shown at 10 which is fixed in the platen frame and is apertured as at 11 at suitable points to accommodate the pressure rollers.

12 and 13 indicate rods or shafts which are extended longitudinally of the platen roll underneath the same in parallel relation therewith, and are supported at their ends in the side pieces 4 and 5 of the platen frame, and mounted to swing upon rods 12 and 13 are brackets 14, said brackets being separated as by means of separating tubes 15 placed upon said rods. Brackets 14 as shown are constituted by side arms 16 integrally joined at their rear ends by the hollow parts 17 which are positioned upon the supporting rods, and each bracket is provided with a rearwardly extending arm 18. Brackets 14 extend in opposite directions from rods 12 and 13, as clearly shown in the drawings, and the arms of adjacent brackets extend toward each other, and lie in adjacency. Each of the brackets is provided with a pressure roller 20, the shaft 21 of which is received in open ended slots 22 of the side arms 16 of the brackets, so as to enable the pressure rollers to be easily removed from the brackets.

The pressure rollers 20 are normally held in engagement with the platen roll by spring means which engages the arms 18 of the brackets. This spring means, in the present instance, is constituted by a double-forked intermediate its ends in a bracket 24, the depending end 25 of which engages rail 2, and is supported upon a pivot pin 26. Each of

the tines 27 of this forked spring engages one of arms 18 of the brackets, and inasmuch as spring 23 is pivotally supported and the tines thereof are of equal length, it 5 will be seen that an equal pressure is applied to each of the arms, and that by reason of this fact the pressure rollers will be held with equal pressure against the platen roll.

The means for releasing the pressure rollers from the platen roll is constituted by an endwise sliding member or rod 28 which rests substantially throughout its entire extent upon the upper rail 2 of the platen frame, said rod being provided with a plurality of projecting portions or cams 30, one of these cam portions being provided for each pair of the oppositely disposed arms 18 of the brackets. Rod 28 is provided with a longitudinally extending slot as at 31, 10 through which extends the end of a bent bracket 32 fastened to the rail 2, which serves as a guide therefor. This bracket carries a leaf spring 33, the ends of which press upon the rod 28 and hold the same 15 in sliding contact with rail 2 and prevent any rattling noise which might occur between these parts during the shifting movements of the platen frame. A spring 34 interposed between the upturned end 35 of 20 rod 28 and the side member 5 of the platen frame, presses said bar to the left, in which position the cam portions 30 are disengaged from the arms 18 of the brackets, and the pressure rollers are, by means of the tines of 25 spring 23, held in contact with the platen roll. Rod 28 is adapted to be slid endwise toward the right to engage the cams 30 with the arms 18 of the brackets by means of a 30 key or finger lever 36, pivoted as at 37 to 35 the side member 4 of the platen frame, the lower end of said lever being provided with a cam portion 38 which engages with an antifriction roller 40 journaled at 41 upon the end of rod 28. The cam portion 38 of 40 finger lever 36 is provided with a notch as at 42, which, when the cam is caused to slide 45 rod 28 endwise, will engage with roller 40 and hold said rod in the position to which it has been moved by the cam, until the 50 finger lever is again manipulated by the operator to release said rod.

The operation of this embodiment of my invention, which should be largely obvious, may be briefly described as follows: It will be understood that when bar 28 is in the position illustrated in Figs. 1 and 3 of the drawings, all the pressure rollers will be in engagement with the platen. When, however, said bar is moved endwise to the right, 55 the cam portions 30 thereof will engage the arms 18 of the brackets and swing said brackets and the pressure rollers carried thereby away from the platen roll, thus releasing the paper. The notch 42 of the cam 60 will engage roller 40 of bar 28 and hold the

parts in this position until released, whereupon spring 34 will return bar 28 to its normal position and allow spring 23 to again engage the pressure rollers with the platen roll.

It will accordingly be seen that I have provided paper feeding mechanism for typewriting machines which will attain, among others, the objects sought in an exceedingly simple, yet efficient manner. The pressure 70 rollers, by means of the provision of the pivotal support for the spring which maintains the pressure rollers in engagement with the platen roll, will be held in contact therewith with equal pressures, thereby insuring 75 an efficient and accurate feed of the paper. The provision of the independent brackets also insures an efficient feeding of paper even though different thicknesses of paper or a greater number of sheets thereof is fed 80 between the pressure rollers and the platen at opposite ends of the machine. The feed rollers may also be readily released from the platen roll to free the paper, and the finger lever for performing this function is in a 85 90 convenient position for manipulation.

As many changes could be made in the above construction and many apparently widely different embodiments of this invention could be made without departing 95 from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a typewriting machine, the combination with the platen frame, a platen roll carried thereby, a plurality of parallel feed rollers running under the platen roll, pivotally mounted carriers for supporting said feed rollers, said carriers being provided with rearwardly extending arms, springs engaging said arms whereby said carriers are moved toward the platen roll and the pressure rollers carried thereby are maintained in engagement therewith, an endwise slideable member provided with cam portions 100 each of which is adapted to engage one of said arms, and a finger lever having a cam which engages said member and moves the same endwise whereby said cams are engaged with said arms and said carriers are 105 swung from the platen roll and locked in disengaged position.

2. In a typewriting machine, the combination with the platen frame and the platen roll carried thereby, of a pair of shafts extended lengthwise of the platen frame and supported in the side members thereof, brackets carried by said shafts, pressure rollers carried by said brackets, said brackets being provided with oppositely extend-

ing arms, a spring means engaging a plurality of said arms to hold the pressure roller carried by the bracket in engagement with the platen roll, an endwise moving bar disposed beneath said arms and having cam portions adapted to engage therewith, and manually operated means for moving said bar endwise whereby the cams thereof are engaged by said arms and the brackets and pressure rollers carried thereby are swung from the platen roll.

3. In a typewriting machine, the combination with the platen frame and the platen roll carried thereby, of a pair of shafts extending lengthwise of the platen frame beneath the platen roll and in parallel relation with the same, a plurality of brackets carried by each of said shafts, a pressure roller carried by each of said brackets, each of said brackets being provided with an arm, spring means engaging the arms of said brackets whereby said pressure rollers are spring pressed toward the platen roll, an endwise sliding bar disposed beneath said arms and having cam portions adapted to be engaged therewith, a spring for holding said bar in normal position, and a finger lever having a cam portion adapted to engage said bar and slide the same endwise to engage said cams with said arms, said cam being provided with means for holding said bar in the position to which it is moved thereby.

4. In a typewriting machine, the combination with the platen frame carrying the platen roll of two sets of pressure roll carriers disposed beneath the platen roll, one set being arranged in advance of the other, shafts each supporting a set of carriers, springs pressing said carriers toward the platen roll, an endwise moving bar having cam portions adapted to engage said carriers whereby the latter may be swung from the platen, and a finger lever provided with a notched cam adapted to move said endwise movable member and hold the same in fixed position after movement.

5. In a typewriting machine, the combination with the platen frame carrying the platen roll, of a plurality of independent brackets pivotally mounted in the platen frame beneath the platen roll, said brackets being provided with rearwardly extending arms, a pressure roller carried by each of said brackets, springs engaging said arms and holding said pressure rollers in contact with the platen roll, an endwise movable rod disposed beneath said arms and having cam portions for engaging the same, a roller carried by said rod, and a finger lever provided with a cam which cooperates with said roller to move said rod endwise whereby the cams thereof are caused to engage said arms and thereby swing said brackets and pressure rollers from the platen roll.

6. In a typewriting machine, the combination with the platen frame carrying the platen roll, of a plurality of pivotally mounted brackets carried by the platen frame beneath the platen roll, a pressure roller mounted in each of said brackets, arms extending rearwardly from each of said brackets, springs engaging said arms whereby the brackets and pressure rollers are urged toward the platen roll, an endwise movable bar disposed beneath said arms and having cam portions adapted to engage therewith, a roller carried at one end of said bar, a finger lever having a notched cam adapted to engage said roller and move said bar endwise, whereby the cams thereof engage said arms and swing said brackets and the pressure rollers carried thereby from the platen roll, the notch of said cam co-operating with the roller engaged thereby to hold said bar in the position to which it is moved by said cam.

7. In a typewriting machine, the combination with the platen frame and a platen roll carried thereby, of a pair of shafts disposed beneath the platen roll which extend in parallel relation therewith and are supported at their ends in the platen frame, a plurality of brackets journaled upon each of said shafts, a pressure roller carried by each of said brackets, and a pivotally mounted spring having independent portions thereof engaged with each of said brackets and operating to urge the same and the pressure rollers carried thereby toward said platen roll.

8. In a typewriting machine, the combination with the platen frame and the platen roll carried thereby, of a pair of shafts disposed beneath the platen frame and extending in parallel relation therewith, said shafts being supported at their ends in said platen frame, a plurality of brackets journaled upon each of said shafts, a pressure roller carried by each of said brackets, a pivotally supported spring having independent portions thereof engaging said brackets and operating to urge said parts and the pressure rollers carried thereby toward said platen roll, and a common means for swinging said brackets simultaneously from the platen roll.

9. In a typewriting machine having a platen frame and a platen roll, the combination of a plurality of pivotally mounted pressure roll carriers disposed beneath the platen roll, and a pivotally mounted spring engaging said carriers and holding the rollers thereof in contact with the platen roll.

10. In a typewriting machine, the combination with the platen frame and the platen roll, of pressure rollers disposed beneath the platen roll and running thereof, independent pressure roll carriers and a pivotally mounted spring member having portions

thereof engaging said carriers and holding the pressure rollers in engagement with the platen roll.

11. In a typewriting machine, the combination with the platen frame and the platen roll carried thereby, of two pairs of rollers disposed beneath the platen roll, one pair being disposed in advance of the other, an independent bracket for supporting each pressure roller, a pivotally supported spring having portions thereof engaging each of said brackets and urging the same toward the platen roll, and a slidable member provided with cams one of which engages and swings each of said brackets when said member is actuated.

12. In a typewriting machine, the combination with the platen frame and the platen roll carried thereby, of pressure rollers disposed beneath the platen roll, arranged in pairs, one pair being disposed in advance of the other, an independent pivotally mounted bracket for supporting each pressure roller, a pivotally mounted spring for each set of pressure rollers having portions thereof engaging each of said brackets and urging the same and the pressure roller carried thereby toward the platen roll, and a slidable member provided with cams one of which engages and swings each of said brackets when said member is actuated.

13. In a typewriting machine, the combination with the platen frame and the platen roll carried thereby, of a pair of shafts disposed beneath the platen roll, extending in parallel relation thereto and supported at their ends in the platen frame, a set of pressure rollers disposed beneath the platen roll comprising two pairs of rollers, one pair being disposed in advance of the other, independent brackets mounted upon said shafts, each of which supports one of said pressure rollers, a pivotally supported spring having portions thereof engaging each of said brackets and urging the same and the pressure roller carried thereby toward said platen roll, and a slidable member provided with cams one of which engages and swings each of said brackets from the platen roll when said member is actuated.

14. In a typewriting machine, the combination with the platen frame, and the platen roll carried thereby, a pair of shafts disposed beneath the platen roll extending parallel therewith and supported at their ends in the platen frame, a plurality of independent brackets mounted upon each of said shafts, and a pressure roller carried by each of said brackets, a pair of rollers being mounted upon one of said shafts, and one of said pairs being disposed in advance of the other, a pivotally supported spring provided with two forked portions, a member of each fork engaging one of said brackets and urging the same toward the platen roll, and a

slidable member provided with cams one of which engages and swings each of said brackets from the platen roll when said member is actuated.

15. In a typewriting machine, the combination with the platen frame and the platen roll carried thereby, of a set of pivotally mounted, independent brackets disposed beneath the platen, a pressure roller carried by each of said brackets, and a forked spring having each of the tines thereof engaged with one of said brackets, and a pivotally mounted support for said spring.

16. In a typewriting machine, the combination with the platen frame and the platen roll carried thereby, of a set of independent pressure roll carriers disposed beneath the platen roll, a pair of shafts disposed in parallel relation beneath said platen rolls upon which said carriers are pivotally supported, a spring having oppositely disposed forked portions each of the tines of which engages one of said carriers and urges the same toward the platen roll, and a pivotally mounted bracket for supporting said spring.

17. In a typewriting machine, the combination with two platen frame and the platen roll carried thereby, of two sets of pressure roll carriers disposed beneath the platen, each set comprising a pair of front and rear carriers, a pressure roller carried by each of said carriers, shafts carried by the platen frame and interposed in the support of said carriers, a spring having oppositely extending forked portions, each of the tines of which engages one of said carriers and normally urges the same toward said platen roll, a pivotally mounted bracket for supporting said spring, and a slidable member common to each of said carriers having cam portions which engage each of said carriers whereby when said member is actuated said carriers will be simultaneously moved from the platen roll.

18. In a typewriting machine, the combination of a platen frame and the platen roll carried thereby, of a plurality of independent brackets pivotally supported underneath the platen roll each of which is provided with an arm, a pressure roller carried by each of said brackets, a spring having oppositely disposed forked portions each of the tines of which engages the upper portion of one of said arms, and swings the bracket toward the platen roll and holds the pressure roller thereof in engagement with the same, a pivotally mounted support for said spring, a slidable rod disposed beneath said arms and having cam portions adapted to engage those parts directly beneath their points of engagement with said springs and swing said brackets when said member is actuated, and a finger lever having a cam portion adapted to engage and actuate said member.

19. In a typewriting machine, the combination with the platen frame and the platen roll carried thereby, said platen frame being provided with a longitudinally extending rail, a pair of pressure roll carriers positioned fore and aft of the machine pivoted beneath the platen roll, pressure rollers carried thereby, spring means engaging said carriers and holding the pressure rollers in engagement with the platen roll, an endwise movable member resting upon said rail and having a cam portion for engaging said carriers to swing the same from the platen roll, and a finger lever for actuating said endwise movable member.

20. In a typewriting machine, the combination with the platen frame and the platen roll carried thereby, said platen frame being provided with a longitudinally extending rail, a plurality of brackets pivotally mounted in the platen frame beneath the platen roll, pressure rollers carried by said brackets, springs coöoperating with said brackets to hold the pressure rollers in contact with the platen roll, an endwise movable member lying in contact with said rail and having cam portions for engaging said brackets and for swinging them from the platen roll, and a finger lever having a cam adapted to engage said member and lock the same in moved position.

21. In a typewriting machine, the combination with the platen frame and the platen roll carried thereby, said platen frame being provided with a longitudinally extending rail, a plurality of brackets pivotally mounted beneath the platen roll, pressure rollers carried by said brackets, said brackets being provided with extending arms, a slideable member lying in contact with said rail, and provided with cam means adapted to engage said arms whereby said brackets and the pressure rollers carried thereby will be swung from the platen roll, means for holding said slideable member in contact with said rail, and a finger lever provided with a cam adapted to engage and actuate said member.

22. In a typewriting machine, the combination with the platen frame and the platen roll carried thereby, said platen frame being provided with a longitudinally extending rail, a plurality of independent brackets pivotally mounted beneath the platen roll, a pressure roller carried by each of said brackets, said brackets being provided with rearwardly extending arms, springs engaging said arms and holding the pressure rollers in contact with the platen roll, and an endwise movable bar resting upon said rail, said bar being provided with a plurality of cam portions adapted to engage said arms whereby said brackets and the pressure rollers carried thereby may be swung from the platen roll, springs engag-

ing said bar and holding the same in contact with said rail, a finger lever provided with a cam portion adapted to engage and actuate said bar, and a spring for returning the same to normal position after each actuation.

23. In a typewriting machine, the combination with the platen frame and the platen roll carried thereby, said platen frame being provided with a longitudinally extending rail, a plurality of independent pressure roll carriers pivotally mounted underneath the platen roll, a pressure roller carried by each of said carriers, arms extending rearwardly from said carriers, springs engaging said arms and holding the pressure rollers in engagement with the platen roll, an endwise sliding bar resting upon said rail and having cam portions, one cam portion being provided for each of said arms, guides fixed upon said rail and engaging said bar, and friction springs secured to said guides and holding said bar in sliding contact with said rail.

24. In a typewriting machine, the combination of a platen roll, a bracket having two arms pivotally mounted beneath said platen roll, a pressure roller supported by one arm of said bracket, endwise movable means engaging the other arm of said bracket adapted to move said pressure roller from said platen roll, and resilient means for returning said endwise movable means to normal position.

25. In a typewriting machine, the combination of a platen roll, a pair of oppositely disposed brackets mounted beneath said roll in a fore and aft direction, a pressure roller carried by each of said brackets adapted to engage said platen roll, and an endwise movable member having a single means adapted simultaneously to engage said brackets and move said pressure rollers from said platen roll.

26. In a typewriting machine, the combination of a platen roll, a bracket pivotally mounted between its ends beneath said roll, pressure roller supported at one end of said bracket, endwise movable means adapted to engage the opposite end of said bracket and move said pressure roller out of contact with said platen roll, and means for locking said endwise movable means in its moved position to hold said pressure roller in a released position.

27. In a typewriting machine, the combination of a platen roll, a plurality of feed rollers in front and in back of the axis of said platen roll and normally in contact with said roll, a bracket pivotally mounted between its ends for each of said pressure rollers, means adapted to engage one end of each of said brackets to swing the pressure roller out of contact with the platen roll, finger-actuated means for actuating said

first-mentioned means, and means associated with said first-mentioned means whereby a continued movement of said finger-actuated means will lock the pressure rollers in a 5 released position.

28. In a typewriting machine, in combination, a platen roll, a plurality of separate pressure rollers coacting therewith arranged in pairs fore and aft of the machine, and 10 a spring between said pairs having a plurality of parts, each adapted to coact with one of said rollers.

29. In a typewriting machine, the combination with the platen frame and the platen roll, of a set of pressure rollers, a forked spring having its tines adapted to hold the rollers in co-operative relationship with the platen roll, and a pivotally mounted support for the spring.

30. In a typewriting machine, the combination with a platen, of a feed roll device including front and rear rolls, hinged brackets rocking independently of each other and supporting the rolls, spring means for pressing the rolls toward the platen, casting-off and restoring mechanism engaging said brackets to drop the rolls from the platen, and means to prevent the brackets from swinging toward each other.

31. In a typewriting machine, in combination, a rotatable platen roll, a plurality of rollers spring-pressed thereagainst, a slideable member movable endwise to force said rollers out of contact with said roll, a pivoted lever movable in a plane at right angles to the axis of said roll for sliding said member to move said rollers, spring means constantly urging said member to free said rollers for pressure against said roll, and means 35 to yieldably lock said lever when operated to slide said member.

32. In a typewriting machine, in combi-

nation, a platen roll, pressure rollers therefor, a tine spring adapted to urge the rollers toward the platen roll, a slide co-operative with said spring, and means comprising a pivoted lever whereby pressure applied by the operator in a transverse direction causes longitudinal movement of said slide, said lever having a substantially long arm on one 45 side of its pivot and comparatively short arm on the other side.

33. In a typewriting machine, in combination, a platen roll, a pivotally mounted bracket carrying a pressure roller on one 50 side of its pivot and having an engaging portion on the other side thereof, a spring adapted to urge the bracket relatively to the platen, and means comprising an endwise movable member and a pivoted lever co-operating therewith, whereby the bracket may be urged in the opposite direction, said lever having arms of different lengths on respectively different sides of its pivot.

34. In a typewriting machine, in combination, a platen roll, a pivotally mounted bracket carrying a pressure roller on one 55 side of its pivot and having an engaging portion on the other side thereof, a spring adapted to urge the bracket relatively to the 70 platen, means comprising an endwise movable member and a pivoted lever co-operating therewith whereby the bracket may be urged in the opposite direction, said lever having arms of different lengths on respectively different sides of its pivot, and means 75 adapted to lock said member in different positions.

In testimony whereof I affix my signature, in the presence of two witnesses.

NILS H. ANDERSON.
